UNITED STATES PATENT OFFICE.

DAVID LUMSDEN, OF CISCO, ILLINOIS.

CLOD-CRUSHER.

No. 878,887.

Specification of Letters Patent.

Patented Feb. 11, 1908.

Application filed August 27, 1907. Serial No. 390,405.

To all whom it may concern:

Be it known that I, DAVID LUMSDEN, citizen of the United States, residing at Cisco, in the county of Piatt and State of Illinois, have invented certain new and useful Improvements in Clod-Crushers, of which the following is a specification.

The present invention provides a novel implement for pulverizing the soil and which will prevent the machine riding over clods or lumps when drawn over the field, thereby insuring the breaking up of lumps of soil of any appreciable size.

For a full understanding of the invention and the merits thereof and also to acquire a knowledge of the details of construction and the means for effecting the result, reference is to be had to the following description and accompanying drawings.

While the invention may be adapted to different forms and conditions by changes in the structure and minor details without departing from the spirit or essential features thereof, still the preferred embodiment is shown in the accompanying drawings, in which:

Figure 1 is a top plan view of a clod crusher embodying the invention. Fig. 2 is a vertical central longitudinal section of the implement. Fig. 3 is a front view of the implement. Fig. 4 is a detail perspective view of a side guide. Fig. 5 is a detail perspective view of a draft hitch. Fig. 6 is a detail view of a tooth and a coöperating brace, the dotted lines showing the relation of the parts when slipping the brace upon the teeth and the full lines showing the position of the brace when finally adjusted.

Corresponding and like parts are referred to in the following description and indicated in all the views of the drawings by the same reference characters.

The implement embodies in its organization, side guides 1 having outwardly extended axle arms 2 upon which are mounted ground wheels 3, each of said guides being provided with a toothed quadrant 4 for coöperation with a lock bar 5 for securing a lever 6 in the adjusted position. The quadrant 4 may be connected to the guide 1 in any manner. A lever 6 is pivoted to the guide 1 at 7 and is provided with a hand latch 8 which is connected with the lock bar 5 for withdrawing the same from engage-

ment with the teeth of the quadrant when it is required to adjust the crushing mechanism. The lock bars 5 are spring actuated and are mounted upon their respective levers 6 in any manner. Standards 9 are slidable in the guides 1 and are provided at their lower ends with bearings 10 in which a shaft or rod 11 is mounted. A rod or bar 12 connects the upper ends of the standards 9. Links 13 connect the lower ends of the standards 9 with the forward ends of the lever 6. The links 13 may be readily disconnected at their lower ends from the standards 9, and for this purpose hooks 14 at the lower end of said standards 9 are adapted to pass through openings in the lower ends of the links 13.

A casting 15 is fitted to each end portion of the shaft or rod 11 and is provided in a side with a depression 16 forming a seat in which the rear end of a bar 17 is secured. The casting 15 consists of a bar having an opening 18 at one end to receive the shaft or rod 11 and having the depression or seat 16 at its opposite end, said bar being provided at the end having the opening 18 with a lug 19 to which a tooth 20 is secured, since the function of the part 15 is to connect the pole or tongue 21 with the implement, which will be designated hereinafter as the draft hitch.

The pole or tongue 21 is connected at its rear end to a rod or bar 22, and the front ends of the bars 17 are bolted or otherwise secured to opposite sides thereof. The bars 17 constitute hounds and are clipped or otherwise secured a short distance from their rear ends to the rod or bar 22.

The crushing mechanism is mounted upon the rod or shaft 11 and comprises, essentially, two parts, a lifting portion and a rotary crushing portion. The lifting portion of the crushing mechanism consists of teeth, whereas the rotary crushing portion comprises a series of rotary members provided with blades. Each rotary member consists of a hub 23 and blades 24, the latter being secured at their inner ends to the hub and having their outer ends pointed and their forward edges sharpened so as to readily penetrate the clods or lumps of soil. The hubs 23 are apertured and receive the rod or shaft 11 upon which the rotary members are mounted so as to turn freely. Spacers 25 are slipped upon the rod or shaft 11 between

each two rotary members so as to separate the same. Each spacer 25 consists of a short bar having an opening at one end to receive the rod or shaft 11 and having a tooth 20 fitted to its opposite end. Braces 26 connect the series of teeth 20 with the rod or bar 22, their upper forward ends being threaded and passed through openings in said rod or bar 22 receiving nuts 27 arranged 10 upon opposite sides of the said rod to admit of adjusting the inclination of the teeth as well as to provide for alinement of said teeth. Each brace 26 is provided at its lower rear end with an eye 28 through which 15 a tooth 20 is passed. A projection 29, upon the front edge of each tooth, engages under the eye of the brace and supports the same. When slipping the brace upon the tooth it is arranged so that the eye 28 occupies a position at a right angle to the tooth, as indicated by the dotted lines in Fig. 6. After the eye 28 clears the projection 29, the upper forward end of the brace 26 is depressed, as indicated by the full lines in Fig. 6, thereby 20 causing the eye 28 to bind the front and rear edges of the tooth and to be held from downward displacement at its rear end by the projection 29.

The teeth 20 and the blades 24 project 30 below a horizontal plane touching the lowest portions of the ground wheels 3 so as to enter the soil. The teeth 20 lift clods or lumps, whereas the blades 24 operating between the teeth and in the rotation of the 35 crusher members, break up said clods or lumps. The distance to which the teeth and blades may penetrate the soil may be regulated by proper adjustment of the lever 6, as will be readily understood.

Having thus described the invention, what 40 is claimed as new is:

1. In a clod crusher, the combination of a main frame comprising approximately vertical guides, standards mounted for vertical movement in said guides, means for adjusting the standards vertically and holding the same in an adjusted position, a rod supported by said standards, means carried by the said rod for lifting clods, and rotary crusher members mounted upon said rod and adapted to coöperate with the clod lifting means for crushing the clods.

2. In a clod crusher, the combination of a rod 22, a rod 11, supporting means for said rods, a series of teeth mounted upon the rod 55 11, braces between said teeth and the rod 22, and rotary crusher members mounted upon the rod 11 and arranged to operate between the said teeth.

3. In combination, side guides, standards 60 movable vertically in said guides, ground wheels supporting the said guides, a rod mounted in the lower ends of said standards, transversely spaced lifting teeth mounted upon the said rod, rotary crusher members 65 mounted upon the rod and arranged to operate between the said lifting teeth, a pole, connecting means between said pole and the aforementioned rod, a rod 22 having connection with the said pole, and braces between 70 the aforesaid lifting teeth and the rod 22.

In testimony whereof I affix my signature in presence of two witnesses.

DAVID LUMSDEN. [L. s.]
